GRIP FOR COOKING RANGE DOOR

Richard E. Hitchcock, Birmingham, Mich., assignor to Sears, Roebuck and Co., Chicago, Ill., a corporation of New York

Application May 6, 1950, Serial No. 9,756

Term of patent 7 years

(Cl. D81—25)

To all whom it may concern:

Be it known that I, Richard E. Hitchcock, a citizen of the United States and a resident of Birmingham, in the county of Oakland and State of Michigan, have invented a new, original, and ornamental Design for a Grip for Cooking Range Door, of which the following is a specification, reference being had to the accompanying drawing, forming a part thereof.

Fig. 1 is a front elevational view of a grip for cooking range door, embodying my new design;

Fig. 2 is a top plan view thereof;

Fig. 3 is a side elevational view thereof; and

Fig. 4 is a vertical sectional view thereof on an enlarged scale.

The dotted lines on the drawing represent fragmentary portions of an associated range door and are for purpose of illustration only.

The ornamental design for a grip for cooking range door substantially as shown and described.

I claim:

The ornamental design for a grip for cooking range door, substantially as shown.

RICHARD E. HITCHCOCK.
